UNITED STATES PATENT OFFICE.

WILLIAM P. OGDEN, OF DENVER, COLORADO.

CONCENTRATOR.

1,004,187.

Specification of Letters Patent. Patented Sept. 26, 1911.

Application filed September 13, 1909. Serial No. 517,457.

To all whom it may concern:

Be it known that I, WILLIAM P. OGDEN, a citizen of the United States, residing in the city and county of Denver and State of Colorado, have invented certain new and useful Improvements in Concentrators; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to improvements in concentrators, my object being to separate the metallic values from the gangue in the treatment of either placer material or pulverized quartz.

20 My improved construction consists of a longitudinally-inclined sluice whose bottom is provided with diagonal grooves, riffles or corrugations, the sluice being also transversely inclined so that the discharge ex-

25 tremities of the grooves on one longitudinal edge of the sluice are more elevated than points directly opposite on the other longitudinal edge of the sluice, the depth of the grooves being sufficient to prevent the concentrates, which enter them, from escaping and traveling directly across the sluice toward the lower, longitudinal edge thereof. The longitudinal incline of the sluice is suffi-

30 cient to cause the concentrates to travel for-

35 wardly in the grooves and discharge at points on one edge of the sluice which are higher than points directly opposite on the other edge. The gangue, however, which is lighter than the concentrates and therefore

40 held in suspension by the water above the grooves or corrugations, flows toward the lower, longitudinal edge of the sluice and is therefore quickly and thoroughly separated from the concentrates producing a re-

45 markably clean product. This is a new principle in concentration, so far as I am aware.

Having briefly outlined my improved construction, I will proceed to describe the 50 same in detail, reference being made to the accompanying drawing, in which is illustrated an embodiment thereof.

In this drawing: Figure 1 is a top plan view of my improved concentrator. Fig. 2 55 is a fragmentary, longitudinal section taken through the bottom of the sluice on the line

2-2, Fig. 1, shown on a larger scale and indicating the transverse inclination of the sluice. Fig. 3 is a side elevation of the apparatus without indicating the transverse 60 inclination of the sluice. Fig. 4 is a rear end elevation without indicating the longitudinal inclination, but showing the transverse inclination. This is a view looking in the direction of arrow 3, Fig. 1. 65

The same reference characters indicate the same parts in all the views.

Let the numeral 5 designate a concentrat- 70 ing sluice, or box, which, as shown in the drawing, is open at both ends. This sluice is provided with side pieces 6 and a bottom 7, to which is applied a rubber covering 8, whose surface is corrugated, as shown at 9, the corrugations being disposed diagonally of the length of the sluice, preferably form- 75 ing an angle of 30 degrees approximately with the sides 6. This sluice or box is lon- 80 gitudinally inclined, as shown in Fig. 3, and transversely inclined as shown in Fig. 4. The bottom of the sluice is provided along the edge uppermost with reference to 85 its transverse inclination, with a longitu- 90 dinal groove or channel 10, into which the concentrates are discharged from the dia- 95 ginally disposed grooves or corrugations of the rubber bottom. The bottom of the chan- 100 nel 10, is provided with openings 12, located at suitable intervals, registering with pipes 13, through which the concentrates may be drawn off from the groove or channel. 90

The box or sluice 5, is supported upon a framework 14, provided with legs 15, there being two legs on each side, the two pairs of legs being located near the opposite extremities of the sluice. Each leg 15, is provided with an angle bracket 16, whose horizontal arm 17, is provided with a threaded open- 105 ing, which is engaged by an adjusting screw 18, whose upper extremity is provided with a crank 19, having an upwardly projecting handle 20, for convenience of manipulation. The lower extremity of each adjusting screw is ball-shaped, as shown at 21, and engages a shallow recess formed in a plate 22. These adjusting screws are employed for regulat- 110 ing both the longitudinal and the transverse inclinations of the sluice, as may be required. It is evident that in treating different classes of material, it may be necessary to change these inclinations, and the adjusting screws make this feature comparatively simple.

The sluice is provided at its upper ex-

tremity with a feed box 23, into which the material to be treated is discharged. This box protrudes into the upper extremity of the sluice and is provided with a discharge opening 24, through which the material in the feed box escapes to the concentrating surface of the sluice. At the lower extremity of the sluice is located a trough 25, adapted to receive the gangue after it has been deprived of its metallic values, which have been caught by the corrugations of the rubber bottom, and discharged into the longitudinal channel or groove 10.

The material to be treated, is discharged into the feed box in the form of pulp, or in combination with sufficient water to form a solution of suitable consistency. As the material is discharged into the feed box, it passes by virtue of its mobile condition directly to the upper extremity of the concentrating surface of the sluice. The downward inclination of the sluice, naturally causes the material to take a downward course, and during its longitudinal passage over the corrugated concentrating surface of the sluice, the metallic values which are heavier than the gangue, stratify or settle in the grooves or corrugations of the rubber bottom, while the water and gangue pass over the corrugations of the rubber bottom, and are discharged into the trough or launder 25.

The transverse inclination of the sluice is an exceedingly important feature, since the metallic values are compelled to move downwardly upon the corrugated concentrating surface of the bottom of the sluice, in order to enter the longitudinal groove or channel 10, at the upper longitudinal edge of the sluice, with which the corrugations of the rubber bottom communicate at their lower extremities. By virtue of this arrangement, the gangue or lighter portion of the material, will naturally travel transversely 40 downwardly, while the metallic values will be caught by the diagonal corrugations or grooves of the concentrating surface, and gradually discharged into the channel 10, the discharge extremities of the diagonal 45 grooves being higher than corresponding points upon the opposite longitudinal edge of the sluice.

It will be understood that the longitudinal and transverse inclinations of the sluice 50 must be so arranged relatively, that the material which settles in the grooves, will follow those grooves downwardly and discharge at the upper longitudinal edge of the sluice. The discharge extremities of these 55 grooves are lower than the extremities or portions of the grooves where the material settles therein, but they are higher than corresponding points upon the opposite longitudinal edge of the sluice. Hence, the 60 lighter material or the gangue which is not

heavy enough to settle in the grooves will quickly separate from the heavy material which settles in the grooves, the lighter material moving transversely downwardly toward the lower transverse edge of the sluice 70 while the heavy material in the grooves cannot get out of the grooves to move transversely downwardly and consequently must continue in the grooves until discharged at the upper longitudinal edge of the sluice. 75 If the concentrating surface of the sluice were smooth, there would be no discharge into the trough or channel at the upper longitudinal edge of the sluice since the heavy material as well as the lighter gangue would 80 all move transversely downwardly and if uninterrupted would discharge at the lower longitudinal edge of the sluice unless the latter were comparatively short in which event some of the material might reach its 85 lower longitudinal extremity. From this it will be understood that with a moderate transverse inclination as indicated in the drawing, the heavy material as the metallic values which settle in the bottom of the 90 diagonal grooves, would have to travel up a steep incline in order to get out of these grooves, but this it cannot do and consequently must continue its downward diagonal direction and discharge into the channel 95 at the upper longitudinal edge of the sluice. The principle is that the heavy material which settles in the grooves must follow 100 these grooves downwardly and discharge at the upper longitudinal edge of the sluice because the material would have to run up a steep hill, so to speak, to get out of the grooves before it could move transversely downwardly. The principle is the same as the flow of water in a ditch formed upon a 105 side hill or mountain slope, in a direction at an angle to the slope. In this case, the water follows the channel of the stream because it cannot get out of said channel. If the bank of the channel were removed on 110 the lower side, the water would take the shortest course down the mountain side. In the same manner if the wall of any groove on the side toward the lower longitudinal edge of the sluice were removed, the material 115 would escape from the groove in the direction of the transverse inclination of the sluice.

The principle upon which my improved concentrator operates, as heretofore explained, is best illustrated in Fig. 2, in which it may be assumed that the upper edge of the view, or that adjacent the letter A, represents the discharge edge of the sluice, while the points B, B', B², B³, etc., are the 120 discharge extremities of the grooves C, C', C², etc. In this case the concentrates which enter the groove C, for instance, are discharged at B⁶, and yet the point B⁶ is higher than the point G on the opposite edge of the 125 130

sluice by a predetermined vertical distance, which for the part of the sluice shown in Fig. 2, is the vertical distance from E to F, and still it is evident that the material cannot get out of the groove C in the direction of the lower, longitudinal edge of the sluice, since in order to do so, it would have to run up the incline H, or uphill, so to speak.

The feed box 23 is equipped with an adjustable finger or separating arm 26, which is pivotally connected with the feed box, as shown at 27. At the upper edge of the said box, this finger divides the feed box into two compartments 28 and 29. The pulp or material to be treated is fed to the compartment 29, which is the larger and which extends toward the lower, longitudinal edge 6 of the sluice; the compartment 28 is toward the upper, longitudinal edge of the sluice and is adapted to receive the wash water. By adjusting this finger, the wash water may be delivered to a greater or less width of the sluice, as may be desired. As this wash water is discharged at the upper extremity of the sluice and at the upper, longitudinal edge thereof, it performs an important function in separating the gangue from the concentrates, the gangue being carried toward the lower longitudinal edge of the table, while the concentrates, which are caught in the diagonal grooves of the sluice, are carried toward the upper, longitudinal edge of the sluice, as heretofore explained.

Having thus described my invention, what I claim is:

1. A stationary longitudinally and transversely inclined concentrating sluice whose bottom is provided with grooves extending diagonally thereacross, the lower extremities of the grooves terminating at the upper longitudinal edge of the sluice and at points which are higher than corresponding points directly across on the opposite side of the sluice, the transverse inclination of the sluice being so regulated as not to tip the material out of the grooves in the direction of its lower longitudinal edge, the bottom of the sluice having a channel extending lengthwise thereof and at the upper longitudinal edge of the sluice, whereby the diagonally arranged grooves of the concentrating surface communicate at their lower extremities with the said channel, substantially as described.

2. A stationary concentrating sluice inclined both longitudinally and transversely, the bottom of the sluice being covered with corrugated rubber, the corrugations being arranged diagonally of the sluice, the bottom of the sluice having a channel formed along its upper longitudinal edge, in which the lower extremities of the grooves of the corrugated rubber surface terminate, the transverse inclination of the sluice being so regulated as not to tip the material out of

the grooves in the direction of its lower longitudinal edge, whereby the concentrates are discharged into the said channel, substantially as described.

3. A concentrating sluice whose concentrating surface is inclined both longitudinally and transversely, the bottom of the sluice being covered with rubber having corrugations extending diagonally of the length of the sluice, the upper longitudinal edge of the bottom of the sluice having a channel to receive the concentrates from the lower extremities of the grooves formed in the corrugated rubber surface, the transverse inclination of the sluice being so regulated as not to tip the material out of the grooves in the direction of its lower longitudinal edge, and means for feeding the material to be treated to the upper extremity of the sluice, substantially as described.

4. A longitudinally and transversely inclined concentrating sluice whose concentrating surface is provided with diagonally disposed grooves, the bottom of the sluice having a channel arranged along its upper longitudinal edge and in communication with the lower extremities of the diagonally arranged grooves of the concentrating surface, the transverse inclination of the sluice being so regulated as not to tip the material out of the grooves in the direction of its lower longitudinal edge, means for feeding the material to be treated to the upper extremity of the sluice, and means for drawing off the concentrates from the said channel, substantially as described.

5. A longitudinally and transversely inclined concentrating sluice whose concentrating surface is provided with diagonally disposed grooves, the bottom of the sluice having a longitudinally disposed channel in communication with said grooves at the lower extremities of the latter, and means for adjusting the said sluice to regulate the degree of both its longitudinal and transverse inclination, the said longitudinally disposed channel occupying a position at the upper longitudinal edge of the sluice, the transverse inclination of the sluice being so regulated as not to tip the material out of the grooves in the direction of its lower longitudinal edge, substantially as described.

6. A concentrating sluice whose concentrating surface is provided with diagonally disposed grooves, the said sluice being inclined both longitudinally and transversely, the degree of longitudinal inclination being such that material fed upon the upper extremity of the sluice and of sufficient gravity to settle in the grooves, will follow said grooves and discharge therefrom at their lower extremities which terminate at the upper longitudinal edge of the sluice, and the degree of transverse inclination being so regulated as not to tip the material out of

the grooves in the direction of the lower longitudinal edge of the sluice.

7. A concentrating sluice inclined both longitudinally and transversely, the concentrating surface of the sluice having diagonally arranged grooves whose lower extremities terminate at the upper longitudinal edge of the sluice, and the degree of transverse inclination of the sluice being so regulated

as not to tip the material out of the grooves 10 in the direction of its lower longitudinal edge.

In testimony whereof I affix my signature in presence of two witnesses.

WILLIAM P. OGDEN.
